SWIVEL CASTER WHEEL OR SIMILAR ARTICLE

Robert I. Moore, North Hollywood, Calif., assignor to Aerol Co., Inc., Los Angeles, Calif., a corporation of California

Application August 12, 1957, Serial No. 47,317

Term of patent 14 years

(Cl. D10—6)

I claim:

The ornamental design for a swivel caster wheel or similar article, as shown.
